[57] **CLAIM**

The ornamental design for a dispensing carton for sheet material, substantially as shown and described.

DESCRIPTION

FIG. 1 is a perspective view of a dispensing carton for sheet material showing our new design;

FIG. 2 is an elevational view showing the end not seen in FIG. 1;

FIG. 3 is a top plan view; and

FIG. 4 is an elevational view thereof showing the side not seen in FIG. 1.

The inner dash lines in FIGS. 1 and 3 represent score lines while the outer and darker dash lines ornamenteally serve to guide the user when opening the carton.

FIG. 1

FIG. 2

FIG. 3

FIG. 4
